UNITED STATES PATENT OFFICE.

ALFRED HENRY GREBE, OF HOLLIS, NEW YORK.

DESIGN FOR A DIAL ESCUTCHEON FOR RADIO APPARATUS PANELS.

Application filed March 6, 1925. Serial No. 12,624. Term of patent 7 years.

To all whom it may concern:

Be it known that I, ALFRED H. GREBE, a citizen of the United States, residing at Hollis, county of Queens and State of New York, have invented a new and original and ornamental Design for Dial Escutcheon for Radio Apparatus Panels, of which the following is a specification, reference being had to the accompanying drawings, forming part thereof.

In the drawings—

Fig. 1 is a view in front elevation of my design for a dial escutcheon;
Fig. 2 is a top plan view thereof, and
Fig. 3 is a side elevation.

I claim:

The ornamental design for a dial escutcheon for radio apparatus panels, as shown.

ALFRED HENRY GREBE.
